CLAIM

The ornamental design for a skin cleansing apparatus, as shown and described.

DESCRIPTION

1. Skin cleansing apparatus

Figure 1.1 is a front view of a skin cleansing apparatus; Figure 1.2 is a back view thereof; Figure 1.3 is a left view thereof; Figure 1.4 is a top view thereof; Figure 1.5 is a bottom view thereof; Figure 1.6 is a front perspective view thereof; Figure 1.7 is a back perspective view thereof; Figure 1.8 is an enlarged view of Figure 1.1; Figure 1.9 is an enlarged view of Figure 1.2; Figure 1.10 is an enlarged view of Figure 1.3; Figure 1.11 is an enlarged view of the handle in Figure 1.1; Figure 1.12 is enlarged view of Figure 1.4; and Figure 1.13 is enlarged view of Figure 1.2.

The broken lines shown in Figures 1.1-1.13 illustrate portions of the skin cleansing apparatus that form no part of the claimed design.

1 Claim, 13 Drawing Sheets
